UNITED STATES PATENT OFFICE.

HENRY G. VOIGHT, OF NEW BRITAIN, CONNECTICUT.

WINDOW-LOCK.

1,042,296.

Specification of Letters Patent. Patented Oct. 22, 1912.

Application filed February 23, 1912. Serial No. 679,809.

To all whom it may concern:

Be it known that I, HENRY G. VOIGHT, a citizen of the United States, residing at New Britain, Hartford county, State of Connecticut, have invented certain new and useful 5 improvements in Window-Locks, of which the following is a full, clear, and exact description.

This invention relates to means for locking together the adjacent rails of window sashes, and in its broad aspect comprises, in combination with a pair of relatively movable sashes, a latch member carried by one of the sashes, a detent carried by the other of 15 these sashes and adapted for locking engagement with the latch member, and means for retracting the detent from locking engagement and for effecting relative movement of the sashes.

20 The invention in its preferable embodiment is illustrated in the accompanying drawings in which—

Figure 1 is a vertical sectional view showing the invention applied to window sashes 25 of the "astral" type. Fig. 2 is a plan view of the parts in locking engagement, the parts of the window sashes being omitted. Fig. 3 is a similar view of the parts with the locking detent retracted. Fig. 4 is a vertical 30 section through the parts on the line 4—4, Fig. 2. Fig. 5 is an enlarged detail view of the base carrying the spring-pressed detent. Fig. 6 is an enlarged detail view of the latch member and its attaching plate. Fig. 7 is an enlarged detail view of the 35 detent member detached. Fig. 8 is a detail view, on an enlarged scale, of the actuating lever.

40 Referring to the drawings by numerals, 1 indicates a window casing in which are mounted window sashes 2—3 provided with roller shades 4 adjacent to their tops and pivoted intermediate their ends at 5. A double armed lever 6 connects these sashes 45 so that when the top of the lower sash is pulled inwardly, a corresponding motion is imparted to the upper sash, the sashes assuming, when fully opened, a parallel position at an inclination of about 45°, as illustrated in dotted lines in Fig. 1 of the drawings. The roller shades or curtains 4 attached to the two sashes, when drawn across the sashes when the latter are tilted as described, form in effect an awning. This 55 type of window sash arrangement is known as the "astral" type, and while my lock is

particularly adapted to such a type of window, it is, of course, susceptible of application to other forms of window.

The locking means proper consists of a 60 plate 8 adapted to be mounted upon the lower rail of the upper sash and provided with a hooked latch member 9 projecting outwardly therefrom. The plate proper is provided with a pulley 10 mounted adjacent 65 to the inner end of the latch member and having thereunder a rope or cable aperture 11. This pulley and its aperture is designed to coöperate with a pulley 7 secured to the top of the upper sash 2 to carry a cord for 70 raising and lowering the shade of the upper sash.

Coöperating with the plate 8 and its latch member 9, and suitably positioned relatively thereto upon the top rail of the lower sash, 75 is a base member 12 suitably secured to this top rail and provided at one end with a housing 13 and at the other end with a raised bed plate 14, a channeled portion 15 being formed therebetween into which the 80 latch member 9 of the opposite sash is adapted to project. Sliding within the housing 13 is a detent shaped to engage with and hold the latch member 9, said detent comprising a head 16 having a beveled front 85 edge 16^a corresponding to the beveled face of the latch member 9 and a straight rear edge 16^b, and having a rearwardly projecting shank 17, the detent head 16 being normally projected out through a recess 18 90 formed in the housing, and the shank 17 extending through an aperture 19 in the opposite face thereof. The detent head is normally projected from the housing by a coil spring 20 mounted upon the shank 17 and 95 within the housing 13, and a guide plate 21 is located within the housing and coöperates with the edge of the detent as it is projected from and retracted in the housing. Extending from the upper edge of the detent head 100 16 is a flange 22 which, when the detent is projected outwardly by the spring, extends across and above the channel 15 to a point adjacent to the edge of the bed plate 14.

It will be obvious from the structure so 105 far described that when the sashes are swung closed, the latch member 9 will be projected into the channel 15 of the base 12 and under the flange 22 of the detent, its rounded end 9^a striking against the beveled face of the detent 16 and forcing it inwardly until the straight edge 9^b of the latch recess 110

clears the end of said detent, whereupon the spring will snap said detent into engagement with the latch recess and prevent relative movement between the sashes until the 5 detent is withdrawn from such engagement by the means which I will now describe.

In order to retract the detent from locking engagement with the latch member, I provide an actuating lever 24 pivotally mounted upon the bed plate 14 by means of a pin 23. This lever has its outer face adjacent to its pivotal point recessed at 25 to form 10 abutment surfaces 26 which engage with a pin or stud 27 mounted in the bed plate in the arc of movement of the abutment members and limit the amount of movement of 15 the actuating lever 24. The inner edge of this lever adjacent to the flange 22 of the detent is provided with an angular extension forming in effect a cam face 28 adapted 20 to coöperate with the flange 22 to retract the detent from locking engagement with the latch member 9. The free end of the actuating lever is formed with an eye 29 25 designed to be engaged by a hook or other hand implement to retract the detent and tilt the window sashes in the manner to be described. The latch carrying plate 8 and the bed plate and housing on the base 12 are 30 each provided with suitable means for securing the same to their respective window sashes, one such means being the countersunk apertures 30 adapted to receive a screw or other suitable securing means.

35 The operation of the lock is as follows: Assuming that the window sashes are closed and that the spring-pressed detent is in locking engagement with the latch member, as shown in full lines in Fig. 1 of the drawings; the operator, by means of a hook or other suitable implement, engages the eye 29 of the actuating lever 24 and turns the same inwardly from the position shown in Fig. 2 to that shown in Fig. 3, the extension 40 28 of this lever engaging with the flange 22 of the detent and pressing the detent head 16 within the housing 13, thereby freeing the latch member 9. Further retracting movement of the lever is prevented by the 45 engagement of the abutment surface 26 with the pin 23. A continued pull on the actuating lever will tilt the window sashes, which can be thus moved to the desired inclination by one continued pull on the actuating lever, 50 which first releases the locking detent and then tilts the window sashes. When the sashes have been tilted to the desired degree of inclination, the actuating lever may be released, whereupon the coil spring 20 will 55 project the detent 16 outwardly, its flange 22 striking against the cam face of the lever and returning it to the initial position shown in Fig. 2. When it is desired to 60 close the window, the hook is inserted in 65 the eye in the actuating lever and a straight

push will bring the sashes back to their original closed position, the pressure on the actuating lever being taken by the pin 27. The detent being independent of the actuating lever, it follows that when the latch member 9 contacts with it, the detent will be forced back in the housing 13 until the sashes have resumed their normal position, whereupon the detent 16 will snap into the recessed portion of the latch 9 and again 70 lock the upper and lower sashes firmly together.

75 It will be noted that the lock, as illustrated, is designed to afford the least obstruction possible to the roller shades and these, therefore, when unrolled, will extend entirely across the glass of the sash.

80 While I have illustrated a preferable embodiment of my invention, it is susceptible of various structural changes and adaptations within the spirit of the invention and of the appended claims. My lock may, for instance, be used with a stationary and a swinging sash and is susceptible of even 85 wider application, for by adaptation it can be used in connection with sashes or other closures in which one of the members moves, swingingly or otherwise, toward and from the other. By the term "relatively movable sashes," I do not, therefore, limit myself to 90 the use of a pair of sashes or even one swinging sash, but mean, broadly, two sashes or analogous structures, one of which moves relatively to the other.

95 What I claim, therefore, and desire to 100 secure by Letters Patent is:

1. A locking device for window sashes comprising a latch member carried by and projecting from one sash to overlap a co-operating sash, a detent carried by a coöperating sash positioned thereon for automatic locking engagement with said latch member, and means movable in one direction to retract said detent from locking position and in another direction to move one of 105 said sashes relative to the other.

110 2. A locking device for window sashes comprising a latch member carried by and projecting from one sash to overlap a co-operating sash, a spring pressed detent carried by said coöperating sash and positioned thereon for automatic locking engagement with said latch member, and means adapted 115 to be actuated to retract said detent from locking position.

120 3. A locking device for window sashes comprising a latch member carried by and projecting from one sash to overlap a co-operating sash, a spring pressed detent carried by said coöperating sash and positioned thereon for automatic interlocking engagement with said latch member, and means adapted upon preliminary movement in one direction to retract said detent from locking 125 position and upon further movement in an- 130

other direction to effect relative movement of said sashes.

4. A locking device for window sashes comprising a latch member carried by and projecting from one sash to overlap a co-operating sash and having a locking recess therein, a spring pressed detent carried by said co-operating sash positioned thereon for automatic interlocking engagement with said recess, an abutment on said detent and a pivoted actuating lever formed and positioned to engage said abutment to retract said detent from locking position.

5. A locking device for window sashes comprising a latch member carried by and projecting from one sash to overlap a co-operating sash and having a recess formed therein, a bed plate mounted upon said co-operating sash and recessed to receive said latch member, a spring pressed detent carried by said plate and adapted for automatic locking engagement with said latch recess, an abutment formed on said detent and a pivoted actuating lever positioned to coöperate with said abutment to retract said detent from locking position.

6. A locking device for window sashes comprising a latch member carried by and projecting from one sash and having a recess formed therein, a bed plate mounted upon a coöperating sash, a spring pressed detent carried by said plate and adapted for automatic locking engagement with said latch recess, an abutment formed on said detent, a pivoted actuating lever positioned to coöperate with said abutment to retract said detent from locking position, and an abutment carried by said bed plate and positioned thereon to be engaged by said lever at the end of its detent retracting movement whereby said lever may be actuated to effect relative movement of said sashes.

7. A locking device for window sashes comprising a latch member secured to and projecting from a sash and having a recess therein, a bed plate positioned on a coöperating sash and having a channel formed therein positioned to coöperate with and receive said latch member, a spring-pressed detent carried by said bed plate adjacent said channel and adapted for automatic

locking engagement with said latch recess, an abutment carried by said detent extending over said channel and latch, and a lever adapted to be actuated to engage said abutment to retract said detent from locking engagement.

8. A locking device for window sashes comprising a latch member secured to and projecting from a sash and having a recess therein, a bed plate positioned on a coöperating sash and having a channel formed therein positioned to coöperate with and receive said latch member, a spring-pressed detent carried by said bed plate adjacent said channel and adapted for automatic locking engagement with said latch recess, an abutment carried by said detent extending over said channel and latch, a lever pivotally mounted on said bed plate and shaped to engage said abutment, when moved, to retract said detent from locking position, and abutments for stopping said lever in detent projected and retracted positions.

9. A locking device for window sashes comprising a latch member secured to and projecting from a sash and having a recess therein, a bed plate secured to a coöperating sash and having a channel therein positioned to coöperate with and receive said latch member, a spring pressed detent mounted on said bed plate adjacent the channel therein and adapted for automatic locking engagement with said latch recess, an abutment flange projecting from said detent and extending over and above said latch, an actuating lever pivotally mounted on said bed plate adjacent said flange provided with a cam surface coöperating with said flange and having spaced abutment shoulders thereon, said lever being adapted, when moved, to engage said abutment flange and retract said detent, and being returned to initial position, when released, by said spring-pressed detent, and an abutment stop positioned on said bed plate to be engaged by said shoulders at the latch projected and retracted positions of said lever.
